To all whom it may concern:

Be it known that I, MILLARD H. PRYOR, a citizen of the United States of America, residing at Owosso, in the county of Shiawassee, in the State of Michigan, have invented a new, original, and ornamental Design for a Range Top, of which the following is a specification, reference being had therein to the accompanying drawing, forming a part thereof, wherein:

The figure is a perspective view of the range top showing my new design.

I claim:

The ornamental design for a range top substantially as shown.

MILLARD H. PRYOR.
